UNITED STATES PATENT OFFICE.

ADOLF A. WINKLER, OF GREAT FALLS, MONTANA.

STREET-INDICATOR FOR STREET-CARS.

1,254,954.

Specification of Letters Patent. Patented Jan. 29, 1918.

Application filed September 27, 1915. Serial No. 52,851.

To all whom it may concern:

Be it known that I, ADOLF A. WINKLER, a subject of the German Empire, residing at Great Falls, in the county of Cascade and 5 State of Montana, have invented certain new and useful Improvements in Street-Indicators for Street-Cars, of which the following is a specification.

This invention relates to improvements in 10 card, picture, and sign exhibiting, and more specifically to street indicators for street cars.

The object of my invention is to provide an indicator which will automatically display to the passenger upon a street car the name of each succeeding street upon the route being traversed by the car. It is a well known fact that the public is greatly inconvenienced and strangers are at an absolute loss to know when they are approaching 20 their destination because of the fact that the conductors either do not call the street at all, or announce them in such a manner that the names cannot be understood by the passengers. It is therefore of great importance to have a visual indicator that will display the street names as such streets are being approached in time for the passengers to give the stop signal. My device is designed to accomplish this in an effective 30 manner, and is so constructed as to embody the features of simplicity, durability, and economy in construction and operation. My device may also be used with equal efficacy upon all manner of electric driven trains, as 35 well as elevators in buildings.

Other objects of this invention not at this time more particularly enumerated, will be clearly understood from the detailed description and drawings forming a part of 40 this application.

Furthermore, this invention consists in the novel arrangement and combination of parts more particularly described in the following 45 specification and embodied in the claims appended hereunto and forming a part of this application.

Referring now to the drawings, which are merely illustrative of my invention,

50 Figure 1 is a front elevation of my improved street indicator for street cars.

Fig. 2 is a similar view with the front cover plate removed.

Fig. 3 is a transverse sectional view taken 55 on the line 3—3 of Fig. 2.

Fig. 4 is a similar view taken on the line

4—4 of Fig. 2 looking in the direction of the arrow.

Fig. 5 is a similar view taken on the line 5—5 of Fig. 2, showing the direction of travel of the tape.

Fig. 6 is a longitudinal sectional view taken on the line 6—6 of Fig. 3.

Fig. 7 is a diagrammatic view of the arrangement of the electrical parts of my invention.

Fig. 8 is a detail view of the electromagnetic brake.

Fig. 9 is a detail elevation of one of the roller bearings.

Fig. 10 is a detail side elevation of the obstacle contact trip.

Fig. 11 is an edge elevation thereof.

Fig. 12 is a detail side elevation of the contact plate.

Fig. 13 is a plan view thereof.

My invention comprises, generally, a route tape mounted upon a spool roller adapted to pass over guide rollers and be wound upon a second spool roller. The lettering upon the 80 tape is so spaced that one revolution of the guide rollers will move it such a distance as will effect the displaying of the next succeeding street name. The invention further comprises electrically controlled means for 85 automatically stopping the tape upon one revolution of said guide rollers, for reversing the direction of travel of said tape, and for completely rewinding the same.

More specifically, 1 designates a casing 90 provided with ends removable to permit access to the adjustable parts of the device. A main window or transparent member 2 is located centrally of the front face of said casing 1 through which may be read the 95 name of the street toward which the car is approaching. Frosted glass signs 3 are located in the front of said casing adjacent the opposite ends of said window 2, said signs containing the name of the car line 100 upon which the indicator is located.

My device is provided with a double bearing support 4 near the rear of said casing 1, and interposed between the bottom and top thereof, there being mounted upon said support drive gears 5 provided each with a centrally located squared recess. The lowermost of said gears is formed with a series of sockets 6 spaced apart circumferentially within the outer face thereof. A plurality 110 of spool rollers 7 are provided having squared trunnions 8 upon their adjacent

2

ends to engage with the recesses in the gears 5, while the opposite ends of said rollers are mounted upon pivoted bearings 9 which may be disengaged therefrom by releasing the 5 supporting catches 10 which are adapted to retain said pivoted bearings in engagement with the ends of said rollers. When it is desired to remove the rollers, it is only necessary to release the supporting catch and 10 swing the pivoted bearing outwardly from the end of the roller, whereby said roller may be withdrawn from the casing. Each of said rollers is formed with a hook 11 centrally with respect to the length thereof.

15 Double bearing supports 12 are mounted forwardly of said spool rollers 7, said bearing supports having mounted therein guide rollers 13 spaced apart one above the other. Said guide rollers are formed with studs 14 20 circumferentially spaced apart near the ends thereof.

25 A route tape 15, constructed of any suitable transparent material, has printed thereon consecutively the street names of the car route being followed by the particular car upon which the indicator is installed. Said tape is formed with a perforation (not shown) centrally disposed near both ends thereof, said perforations being adapted to 30 engage with the hooks 11 respectively upon the spool rollers 5. Said tape is also formed with a plurality of spaced perforations 16 upon both sides and along the length thereof, said perforations being adapted to engage 35 with the studs 14 upon the guide rollers 13.

40 Tension rollers 17 are mounted between the spool rollers 5 and the guide rollers 10, said rollers 17 being carried by the free ends of arms 18, the latter being pivoted to the double bearing support 12. Coil tension springs 19 are interposed between said tension rollers, the tape 15 being passed beneath the uppermost of said tension rollers and 45 over the lowermost of said tension rollers whereby the said tape is maintained in a perfectly smooth and taut state, as illustrated in Fig. 5 of the drawings.

50 An electric motor 20 is mounted within said casing near one end thereof and a drive pinion 21 mounted upon the shaft of said motor is adapted to mesh with the lowermost of said gears 5, thereby transmitting motion to said gears, to the rollers interposed between 55 said gears and the pivoted bearings 9, thence to the tape 15 wound upon said rollers.

60 The electro-magnetic brake of my invention consists of an electro-magnet 22 which is mounted upon a standard 23 within said casing in close proximity to the lowermost of said gears 5, and a spring contact arm 24 mounted at one end upon the standard 23, having the other end disposed downwardly 65 intermediate the end of the magnet 22 and

the lowermost of said gears 5. The face of the free end of said contact arm is formed with a semi-spherical boss 25 which, when engaged with one of the sockets 6 formed in the face of said gear will act as a brake 70 thereon. Said contact arm is normally retained in engagement with said gear by means of a spring tension member 26 secured at one end thereof to the free end of said arm and at the other end to an L-shaped 75 anchor member 27.

80 A standard 28 is mounted within said casing near one end of the rollers 7 and 13. A three-point stopping switch 29 of the standard pull type is mounted upon the upper end of said standard, there being secured therein, a spring, not shown, to normally hold the switch in operative position. An L-shaped contact arm 30 extends downwardly therefrom and its shorter arm 85 is disposed forwardly to a point adjacent the lower portion of the lowermost of said guide rollers 13. A wiper 31 is eccentrically mounted upon the end of said roller 13 whereby said arm will be actuated 90 downwardly upon each revolution of said roller 13.

95 The arm is normally held in raised position by the spring in the switch. The switch will not be thrown until the disk is moved to the position shown on Fig. 4 of the drawing, whereupon the arm will be pushed downwardly and the spring in the switch will pull the same. As soon as the disk passes the center, the arm 30 will be moved 100 upwardly by the tension of the spring and the switch will once more resume its original position.

105 A three-point starting switch 32 is mounted upon a standard 33 near said stopping switch 29, said starting switch being actuated by means of an electro-magnet 34 mounted beneath said starting switch and connected thereto by an armature 35 operatively disposed above said magnet and having a 110 connecting rod 36 interposed between the free end of said arm and said switch. The armature 35 is a spring arm secured to the casing and normally disposed out of engagement with the electromagnet.

115 A metallic plate 37 is mounted within said casing at a point forwardly thereof and slightly above the lowermost of said guide rollers 13. A plurality of lamp sockets 38 are mounted in spaced apart relation upon said plate, electric lamps 39 being mounted in said sockets. The lamp near the end of the casing where the motor is located may be mounted horizontally upon a vertically disposed standard 40 in the event that said motor consumes so much space as to make it impracticable to mount the lamp directly in front thereof. From this it is obvious that the end lamps are directly to the rear of the glass signs 3, and that the intermediate 120 125 130

lamps are spaced apart just behind the route tape 15.

A copper contact member 41 secured at one end to a flexible metallic strip 42 is mounted 5 upon a trolley wire by means of a clamp 43. A trip member, consisting of outwardly extending contact arms 44 is mounted upon a trolley pole 45 by means of a clamp 46, there being interposed between said clamp and 10 said pole an insulator 47.

My device is controlled by a series of switches arranged in circuit with the various parts thereof. The controlling switches are conveniently located in a switch box in the 15 car, and consist of a pair of fused knife switches 48 and 49, a double-throw double-pole switch 50 for reversing the rotation of the motor, and a four-point switch 51 for completely rewinding the route tape 15.

20 One of the main fused switches 48 is connected in circuit with the electro-magnet 34 controlling the starting switch 32, while one of the fused terminals is connected to the trip member 44 on the trolley pole 45 by means 25 of a wire 52, while the other terminal is connected with the ground wire 53'.

The switch 49 is connected by means of conductors 48' and 49' to the electric-motor 20, the four-pole double throw switch 50 30 being interposed in the motor circuits to reverse the direction of the motor as desired. This switch and its connections are of a standard form and will not be described in detail. The lamps 39 are shown interposed 35 in a circuit *a* controlled by a switch S.

In order to control the motor automatically I have provided the three-pole switches 29 and 32, the switch 32 being controlled by the electro-magnet 34, said electro-magnet 40 being interposed in conductors 50' leading from the knife switch 48. Conductors 53 and 54 serve to carry the current from the starting switch to the terminals of the rewinding switch 51, said conductors being 45 continued as at 55 and 56 and connected to the stopping switch 29. The conductor 48' continues on the far side of the stopping switch and is connected with one of the arms of the motor reversing switch 50. The electro-magnets 22 are shunted 50 across and operate in a manner which will hereinafter appear.

In operation the switches 48 and 49 are closed permanently and the switch 50 set 55 whereby the motor will turn in the proper direction for winding the tape. When one of the contact arms 44 engages the trip on the trolley wire current will flow through the conductor 52 to the conductor 50' energizing the electro-magnets 34. When the 60 electro-magnets 34 are energized the switch 32 will be moved to a given position, said position being opposite to that of the stopping switch, so that current will flow, in one 65 instance through the conductor 53, switch 51,

conductor 55 and then through the switch 29 to the reversing switch 50. This supplies current to the motor 20 and also the electro-magnet 22. The action of the electro-magnet 22 and the motor is practically 70 simultaneous, but the brake member will quickly disengage from the roller and permit the motor to rotate the same, exhibiting the next stop. The mechanism of the starting and stopping switches is of a standard 75 make now in use and need not be described in detail herein. If it is desired to rewind the tape when the car is to return, or for any other reason, the switch 51 will be thrown from the position shown to connect 80 the conductors 54 and 56 thereby delivering current to the motor. Of course, it is necessary that the reversing switch be moved to the position necessary to cause the rewinding 85 of the tape.

As has been hereinbefore stated, the armature of the electromagnet 34 comprises a spring arm, that is normally held out of engagement with the magnet, and when in such position the switch 32 is in normal position, and the motor is out of the operating circuit. When the switch 49 is closed, and the electromagnet energized by operation of the tripping mechanism, that makes the contact with the trolley wire, the armature 35 90 will be drawn down and the switch 32 thrown. This will operate the motor and consequently start the indicator to wind. The shunt circuit through the conductor 60 to the electromagnet 34 will keep the said 95 electromagnet energized, when the contact is broken with the trolley wire, until the indicator tape has moved the required distance.

When the tape has been wound the required distance the arm 30 that is operated by the eccentrically mounted wiper disk 31, will throw the switch 29 temporarily, thereby breaking the circuit and stopping the operation of the indicator. This will likewise release the armature 35 of the electromagnet 34 and return the switch 32 to normal position. The braking mechanism which then has been applied will stop the indicator. When the switch 29 once more 110 returns to normal operative position the various parts of the device are in position to operate once more upon contact being made with the trolley wire.

What I claim as my invention and desire 115 to secure by Letters Patent is:

1. In a changeable exhibitor, the combination with a route tape and rollers upon which said tape is to be wound, a motor, and means connecting the rollers operatively 120 with the motor to be driven thereby, of a supply circuit, a branch circuit, magnetically operable means to close the circuit of the motor and being controlled by said branch circuit, and a magnetically released brake 125 130

for engagement with one of the rollers, said brake adapted to be released when current is supplied to the motor circuit.

2. In a changeable exhibitor, the combination with a route tape and rollers upon which said tape is to be wound, a motor, and means connecting the rollers operatively with the motor to be driven thereby, of a supply circuit, a branch circuit, magnetically operable means interposed in the branch circuit to close the circuit of the motor, a brake for engagement with one of the rollers when said motor stops, an electro-magnet shunted across the motor circuit and operable to withdraw said brake from engagement with the roller when the motor circuit is closed for the purpose specified.

3. In a changeable exhibitor, the combination with a route tape and rollers upon which said tape is to be wound, a motor, and means connecting the rollers operatively with the motor to be driven thereby, of a supply circuit, a branch circuit, magnetically operable means interposed in the branch circuit to close the circuit of the motor, a circuit closer operable by mechanical engagement with one of the rollers to break the motor circuit after each revolution of

said roller to stop the motor, and a brake engageable with one of the rollers, said brake being disengaged from operative position by magnetic means communicating with the motor circuit and adapted to be energized when the motor is started.

4. In a changeable exhibitor, the combination with a route tape and rollers upon which said tape is to be wound, a motor, and means connecting the rollers operatively with the motor to be driven thereby, of a supply circuit, a branch circuit, an electro-magnet interposed in said branch circuit, a starting switch for the motor interposed in the circuits thereof, a stopping switch interposed in series with said starting switch, said starting switch being operable by said electro-magnet when the branch circuit is energized, an electro-magnetic brake operable to release the rollers upon energization of the motor circuits, and a double-throw switch interposed between said starting and stopping switches to completely rewind the tape when required.

In testimony whereof I affix my signature hereto.

ADOLF A. WINKLER.
